[57] **CLAIM**

The ornamental design for a showerhead display cabinet, as shown and described.

DESCRIPTION

FIG. 1 is a perspective view of my showerhead display cabinet showing my new design;

FIG. 2 is an elevational view taken from one side thereof;

FIG. 3 is a front elevational view thereof;

FIG. 4 is a top plan view thereof;

FIG. 5 is an elevational view taken from the side opposite that shown in FIG. 2; and

FIG. 6 is a rear elevational view thereof.

The flexible hose has been broken away for convenience of illustration in FIGS. 2, 3, 4 and 5.
